[57] CLAIM

The ornamental design for an artist palette, as shown and described.

DESCRIPTION

FIG. 1 is a top perspective view of an artist palette showing my new design;

FIG. 2 is a top plan view thereof;

FIG. 3 is a front elevational view, the rear view being a mirror image thereof;

FIG. 4 is a side elevational view, the side opposite being a mirror image thereof;

FIG. 5 is a bottom plan view thereof;

FIG. 6 is a top perspective view of a second embodiment of my new design;

FIG. 7 is a top plan view of FIG. 6;

FIG. 8 is a front elevational view of FIG. 6, the rear view being a mirror image thereof;

FIG. 9 is a side elevational view of FIG. 6, the opposite side being a mirror image thereof; and,

FIG. 10 is a bottom plan view of FIG. 6.
